UNITED STATES PATENT OFFICE.

EDWARD O'TOOLE, OF GARY, WEST VIRGINIA.

MINING-MACHINE TOOL.

Application filed June 15, 1926. Serial No. 116,115.

This invention relates to mining machine tools and more particularly to a combined conveyer flight and cutting tool, and has for its object the provision of a novel form of tool adapted to be secured to and propelled by a single chain and to both undercut and convey the material being mined.

Heretofore mining machines have been constructed with a cutter chain having cutter bits secured thereto and a separate conveyer chain having conveyer flights secured thereto for conveying away the mined material, therefore necessitating two separate chain mounting and drive mechanisms.

The present invention eliminates the use of one chain, its mountings and drive mechanism, thereby materially reducing the cost of manufacture and simplifying the machine construction.

Another and important object of the present invention is to provide a cutting tool or bit mounting which may be bodily adjustable to direct the bits at various angles from a horizontal plane, thereby eliminating the necessity of separately adjusting each of the several picks.

In the drawings:

Figure 1 is a plan view of a section of cutter chain having my combined conveyer flight and cutting tools mounted thereon.

Figure 2 is an enlarged side elevation, and Figure 3 is a plan of the forward end of the combined conveyer flight and cutting tools of Figure 1.

Figure 4 is an enlarged side elevation, and Figure 5 is a plan of the forward end of a slightly modified construction of conveyer flight and cutting tool.

Figure 6 is an enlarged side elevation, and Figure 7 is a plan of the forward end of a second modified construction of conveyer flight and cutting tool.

Referring more particularly to the drawings, the letter A designates the tool or cutter chain, which may be of standard design and construction, and the letter B designates the combined conveyer flight and cutting tools as a whole which are pivotally mounted on the chain as at 2.

Each of the combined conveyer flight and cutting tools B comprises an elongated body portion or flight-bar 3, which has its free end thickened vertically and shaped to receive a cutting tool-head 4 in which cutting

bits 5 are removably mounted.

Each of the tools B of Figures 1 to 3 is provided at its free end with an upwardly and forwardly projecting tongue 6 which has its side faces serrated as at 6^a, and is provided with a centrally arranged horizontal aperture 7. The tool-head 4 of Figures 1 to 3 is composed of two cooperating blocks 8 and 9 which have their abutting faces relieved to fit around the tongue 6 and are apertured at 10 to correspond with the aperture 7. The side faces of the relieved portions of the blocks are serrated as at 12, to intermesh with the serrations 6^a on the tongue 6. A bolt 13 is passed through the apertures 7 and 10 and provided with a nut 14 so that the blocks 8 and 9 may be rocked or pivoted about the bolt 13 and locked in adjusted position by screwing home the nut 14, thus forcing the serrations 6^a and 12 to intermesh.

The abutting faces of the blocks 8 and 9 are further relieved to form tool or cutter bit receiving recesses 15 and 16, and are apertured to receive a bolt 17 adjacent their forward ends adapted to clamp the blocks 8 and 9 against the bit shanks.

In the construction of Figures 4 and 5 the tool B is provided with a pair of upwardly and forwardly projecting spaced ears 19 which are apertured horizontally to permit the bolt 20 to pass therethrough. The tool-head 4 of this construction is composed of a single block having a tongue 21 at its rear end adapted to fit between the ears 19 and provided with an elongated hole 22 through which the bolt 20 is passed. The rear face of the head at each side of the tongue is provided with a plurality of serrations 23 adapted to be intermeshed with cooperating serrations 24 on the ears 19 to prevent rotation of the head about the bolt 20. The elongated hole 22 will permit the head 4 to be moved or reciprocated to unmash the serrations when the nut on the bolt 20 is loosened so that the head may be rotated about the horizontal axis of the bolt. After the head has been adjusted it will be moved rearwardly relative to the bolt 20 and ears 19 and locked in position by tightening the nut of the bolt 20.

The head 4 of this construction is provided with a pair of sockets or recesses 15^a in which the cutting bits 5 are mounted and locked by set-screws 25.

In the construction of Figures 6 and 7 the

tool B is provided with a pair of upwardly and forwardly projecting spaced ears 26 which are apertured horizontally to permit the bolt 27 to pass therethrough. The tool 5 head 4 of this construction is composed of a single block having a tongue 28 at its rear end adapted to fit between the ears 26, and provided with a hole 30 through which the bolt 27 is passed. The ears 26 and the forward end of the bar portion 3 of the tool are slotted as at 31, to receive a key 32 which has its forward face serrated as at 33, which serrations are adapted to mesh with corresponding serrations 34 in the rear face of 10 the tongue 28.

The head 4 of this construction is provided with a pair of sockets 15^b or recesses in which the cutting bits 5 are mounted. The bits 5 being locked in position by 20 screws 35.

In each of the several constructions or embodiments of my invention, the head 4 is adjustable about a horizontal axis relative to the bar portion 3 of the tool, so as to cut a 25 kerf up or down without changing the position of the cutter bits in the head.

In the construction of Figures 1 to 3, in order to adjust the position of the head 4, the nut 14 on the bolt 13 is loosened to permit 30 the unmeshing of the serrations 6^a and 12, and the head 4 is then free to move about the horizontal axis of the bolt 13 relative to the bar or flight portion 3, and when the adjustment is completed the nut 14 is again screwed home on the bolt 13 to lock the serrations 6^a and 12 in mesh.

In the construction of Figures 4 and 5, in order to adjust the position of the head 4, the nut on the bolt 20 is loosened sufficiently 40 to permit the longitudinal reciprocation of the head 4 relative to the bar 3 and bolt 20 so as to disengage the serrations 21 and 23. The head is then rotated about the horizontal axis of the bolt 20 and then shifted or reciprocated rearwardly to again mesh the 45 serrations 21 and 23, and the nut on the bolt 20 tightened to lock the head 4 and bar 3 against relative longitudinal movement.

In the construction of Figures 6 and 7, 50 in order to adjust the head 4, the nut on the bolt 27 is loosened and the key 32 is withdrawn so as to permit free rotation of the head 4 about the horizontal axis of the bolt 27 relative to the flight or bar portion 3.

55 After the head 4 is adjusted the key is

again inserted in the slot 31 and the nut on the bolt 27 tightened to lock the head 4 against movement.

While I have shown and described certain specific embodiments of my invention, it will be expressly understood that I do not wish to be limited thereto since various modifications may be made without departing from the scope of my invention as defined in the appended claims.

I claim:

1. A combined conveyer flight and cutting tool for mining and loading machines comprising an elongated flight-bar, and a cutting tool-head removably mounted on one 70 end of and adjustable about a horizontal axis relative to said flight-bar.

2. A combined conveyer flight and cutting tool for mining and loading machines comprising an elongated flight-bar, a cutting 75 tool-head pivotally mounted on one end of and adjustable about a horizontal axis relative to said flight-bar.

3. A combined conveyer flight and cutting tool for mining and loading machines comprising an elongated flight-bar, a cutting tool-head pivotally mounted on one end of and adjustable about a horizontal axis relative to said flight-bar, and means for locking 80 said head in various adjusted positions.

4. The combination with a cutter chain of a mining machine, of a plurality of combined conveyer flight and cutting tools pivotally secured at spaced intervals to said chain, each of said conveyer flight and cutting tools comprising an elongated flight-bar, a cutting tool-head removably mounted on one end of and adjustable about a horizontal axis relative to said flight-bar, said cutting tool-heads having openings therein 85 for the reception of cutting bits, and means for securing said bits in position.

5. The combination with a cutter chain of a mining machine, of a plurality of combined conveyer flight and cutting tools pivotally secured at spaced intervals to said chain, each of said tools comprising an elongated flight-bar, a cutting tool-head pivotally secured to one end of said flight-bar and adjustable about a horizontal axis relative to 100 said flight-bar, and cutter bits removably secured in said heads.

In testimony whereof, I have hereunto set my hand.

EDWARD O'TOOLE.
